UNITED STATES PATENT OFFICE.

MICHAEL J. CALLAHAN, OF NEW YORK, N. Y.

HEATING AND VENTILATING UNIT.

Application filed January 19, 1924. Serial No. 687,199.

This invention has reference to ventilating apparatus or, so-called, ventilating units, and particularly has reference to devices, apparatus or units adapted for individual installation in schools, houses, lofts and buildings generally, as well as where the usual heating and ventilating apparatus or systems would be impracticable or too expensive.

- Among the objects of my invention may be noted the following; to provide a heating and ventilating machine, apparatus or unit which is adapted to be located in a room, the temperature of which is to be controlled, and to be installed at a window and around a radiator, or around the latter in places where an opening may be made in the building wall for the ingress of air, said unit to have a certain mode of operation imposed thereon by mechanism of my invention; to provide a unit, such as referred to, comprising certain essential elements which are adapted to supply fresh air from the outside of the building, heat said fresh air to the desired temperature, and deliver the heated air into the room or space where the apparatus or unit is located under control of certain mechanism of my invention; to provide a heating and ventilating unit adapted to convert fresh, cold air into air heated to the desired temperature, and deliver the same to the room or space where the apparatus is located, and also to control the operation of such apparatus or unit through novel mechanisms or devices of my invention which are affected by changes of temperature in the said room; to provide a strong, durable, compact and effective apparatus adapted for producing the results and functions noted in the foregoing, and which, in its operation, is controlled by the temperature in the room where the unit is located, and, under such control, is adapted to take in cold, fresh air and deliver the same into the room heated to the desired temperature; to provide an apparatus, machine or unit of a type such as described in the foregoing which is so constructed as to prevent the radiation of heat into the room or space where the unit is located, as distinguished from delivering heated air into such room or space; to provide details of construction such that the apparatus or unit may deliver all hot air into the room, all cold air into the room, or air so heated under thermostatic control of dampers that the air passing through the unit may be delivered into the room at practically any temperature which may be desired

or which may be predetermined according to the adjustment of a thermostatic or similar controlling device; to provide for the intake of cold, fresh air through the wall of the building, the delivery of said air to a blower, and the delivery of said air from the unit either hot or cold, or heated to the desired or predetermined temperature, the results being brought about either by automatic controlling means or hand controlling means; to provide an apparatus of the type noted in the foregoing, and capable of producing the functions and carrying out the modes of operation stated, with cleaning and humidifying means, whereby the air passing through the apparatus may be cleansed of impurities or particles and delivered into the room of location of the apparatus with more or less of humidity; to provide means by which recirculation of air through a unit apparatus may be provided for, and by which cold air may be delivered directly from the outside of a building through the apparatus into the room where the latter is located without being tempered by the heat in the apparatus; to provide certain novel devices in a heating and ventilating unit including (1) a duplex damper the parts of which are simultaneously operated and which control the direction in, through and from the radiator of the cold, hot and tempered air, (2) thermostatic controlling means for said duplex damper which imposes certain novel modes of operation upon the duplex damper and produces improved and new results in a unit apparatus, (3) a toggle mechanism for operating the duplex damper, (4) means for directing and deflecting the air in the apparatus for various novel functions, (5) means for dividing the casing into distinct, but intercommunicating, chambers adapted to certainly bring about novel results in a heating and ventilating unit, (6) to provide, in combination with the foregoing novel features, humidifying and cleansing means adapted to treat the hot air only passing through the unit, and (7) to bring about, in the unit, more positive results than heretofore possible both in the delivery of hot air and cold air from the apparatus; to provide a form of radiator which produces a maximum of B. t. u.'s., with a minimum of heating fluid, economically, simply and effectively, and which is light, strong, durable and provides ample radiating surface in apparatus of predetermined size and for predetermined purposes; and to

provide certain details of construction which are strong, durable and effective and which are compactly and economically disposed in the apparatus, adapted to carry out the modes 5 of operation and produce the functional results hereinbefore noted.

With the above objects in view and others which will be detailed during the course of 10 this description, my invention consists in the parts, features, elements and combinations thereof hereinafter described and claimed.

In order that my invention may be clearly understood, I have provided drawings 15 wherein:

15 Figure 1 is a view showing in front elevation a unit heating and ventilating apparatus embodying my invention, with parts broken away to show details of construction, and with a thermostatic controlling device diagrammatically shown for purposes of illustration, the duplex damper in this figure being shown in the closed position;

Figure 2 is a section substantially on the line 2—2 of Figure 1, showing details of construction of Figure 1 and the duplex damper for controlling the flow of air through the apparatus set to the opposite extreme or entirely open;

Figure 3 is a view similar to Figure 2, but 30 showing a different form of apparatus in certain essential details;

Figure 4 is a view similar to Figure 3 showing only the upper part of the apparatus embodying another form of my invention; and

35 Figure 5 is a view similar to Figure 4 showing hand operated means for controlling the duplex damper.

Referring to the drawings, Figures 1 and 2, the base of the apparatus is composed of the 40 outer, vertical sheet metal members 1 so combined as to produce a rectangular casing of any desired dimensions. As shown in Figure 2, the bottom member 2 and the back wall or member are of single thickness sheet metal, while the front wall and side walls, see Figures 1 and 2, are made double by adding an inner sheet metal casing 3, separated from the casing 1 sufficiently to produce an air chamber 4, in which dead air exists, which 45 is adapted to insulate the outer walls from the inner walls to prevent heat conduction from the radiation chamber 5, in which the radiating unit 6 is located. This radiator or radiation unit is composed of a plurality of 50 tubes which may be of any length, cross-sectional shape and diameter desired, and which may be made of any light metal such as copper, brass, tin, or other sheet metal, or which may be drawn or cast as may be found desirable or economical. These radiator tubes are 55 connected at their opposite ends to sealed headers providing inlet chamber 7 and outlet chamber 8, and which are in the form of rectangular end casings common to all the tubes. 60 Said chambers are, respectively, provided

with inlet and outlet pipes 9 and 10, which pass through the casing of the unit and are properly connected in the fluid supply and drainage system forming part of the heating plant. By thus constructing the radiator it 70 is light, strong, durable and economical of production. As shown in Figures 1 and 2, the said radiator as a whole is supported in the base of the apparatus on suitable angles 8^a between the front and back walls and two 75 end or side walls and occupies nearly all the space within the base of the apparatus excepting only a small chamber at the bottom of the base in which the cleaning and humidifying pan 11 is located. The space or chamber 80 below the radiator in which the water pan is located is properly termed the humidifying chamber and is indicated by 12.

As shown in Figure 2, the radiator is so constructed as to give to its upper end or surface an obtuse angular form, and an extreme upper horizontal portion. The radiator occupies all of the heating chamber 5 excepting a small portion just below the motor board 14, which latter extends across and closes the top of the heating chamber. The front of the motor board has openings 15 through which the fresh air may be driven from the fans or blowers presently described. The casing above the heating chamber is formed

into a motor and blower chamber 16 closed by a front plate 17 hinged at its bottom at 18 and locked in position in any suitable way at its top 19. The top member of the blower chamber, indicated at 20, is provided with an opening across which a grille 21 is placed to prevent articles from passing therethrough, the chamber 16 at its top under the grille 21 being provided with a rectangular damper chamber 22 formed by the casing members 23. Within the chamber 16 and mounted upon the motor board 14 an electric motor 24 is located and supported in any suitable manner, so that its shaft 25 may be extended laterally in opposite directions and have mounted thereon at its opposite ends the blowers 26, which are preferably in the form of centrifugal fans which take the air in from the chamber 16 at the eye or axis thereof.

The fans or blowers are located directly over the openings 15 in the motor board and are surrounded by fan shields 27 which confine and direct the air, slipping off the blades of the fans, directly downwardly from their flared ends through the openings 15 in the motor board, the shields being so formed and disposed as to close the back of the fans at the surface of the motor board, as at 28, and leave a large opening from the said shields

communicating with the openings 15 into the base of the apparatus. Below the motor board 14, and directly under the openings 15 thereof and extending entirely across the base 1 at the top thereof, and above the obtuse 115 angular portion of the radiator, is a by-pass

130

chamber 29, the inlet to which is from the motor and blower chamber 16 through the openings of the motor board 15 and the outlet from which is through the discharge opening 30 at the top of the base and at the front of the casing below the hinge 18 of the front plate 17. The discharge opening at 30 is protected or covered by a grille of wire material the same as at 21 or opening of the chamber 22. The by-pass chamber 29 may be made as extensive as is found to be necessary by regulating the size of the radiator 6 in the heating chamber 5; and said by-pass chamber 29 is bounded by the double casing walls at its front and opposite ends, by the radiator 6 at its bottom, by the motor board 14 at its top and by the baffle plate 31 at its back. Secured to the motor board 14 at the rear wall of the openings 15 is the curved baffle-plate 31 which depends into the by-pass chamber, and separates the back of the latter from the heating chamber 5, the baffle also having the function of a support and limiting means for one member of the duplex damper presently described. A support for the other member of the duplex damper is in the form of a ledge 32, composed of an angle of metal secured to the inner wall 3 of the casing at the front of the heating chamber just above the top of the radiator, the said ledge being so located as to arrest the member of the duplex damper in a horizontal position simultaneously with the contact of the other member of the duplex damper with the baffle and support 31. At opposite ends of the by-pass chamber 29, guideways are formed by pairs of angles 33 spaced apart and in parallelism and secured to the inner side walls 3 of the casing base. The guiding channel or guideway between the two angles 33 affords a track for the opposite ends of a rod 34, which ends may be provided with anti-frictional means cooperative with the walls of the guideways. The rod 34, at its opposite ends, adjacent the angles 33, has swiveled thereon for circular movement pairs of arms or links 35 respectively connected pivotally at their lower ends, as at 36, to ears or lugs extending from the members 37 and 38 of a duplex damper, the inner ends or edges of which damper members are pivotally mounted upon a rod 39 fixed at its opposite ends to the opposite end walls of the casing base at the vertex of the obtuse angle forming one part of the top of the radiator or at the bottom of the by-pass chamber 29. In Figure 2, the open position of the duplex damper is shown in full lines and the closed position of said damper is shown in dotted lines. The rod 34 is raised and lowered in the guiding channel or track between the angles 33 by means of the vertically extending, centrally disposed rod 40 swiveled to the rod 34 at its lower end and pivotally connected at 41 to the outer end of the horizontal lever 42, pivotally mounted at its inner end, as at 43, to a lug depending from the casing 44 of an air motor of well-known form operated pneumatically under thermostatic control, as presently described. The plunger 45 of the motor is pivotally connected to the lever 42 near the pivotal point 43; and the lever 42 is normally partially sustained in horizontal position by the spring 46, which also has the function of aiding in the collapse of the bellows of the motor 44 by lifting the lever 42 after it has been depressed by the plunger 45 of the motor, and has the further function of lifting the members of the duplex damper when occasion requires, according to the rule of operation of the apparatus. The motor has leading thereto a pipe 47, which conveys the air from the source of compressed air, said pipe being connected in usual manner by a valve with the thermostatic controlling means indicated only diagrammatically at 48, Figure 1.

Details of the thermostatic control and of the motor or operating means are not disclosed, since specifically such details form no part of my invention; but, it is well understood that, when the controlling device is set at a predetermined degree for temperature in the room where the apparatus is located, and the temperature reaches that degree, the controlling means will admit air to the pipe 47, which will expand a bellows or operate a pump in the casing 44, resulting in causing the plunger 45 to descend and swing the lever 42 downwardly around its pivot 43, and thus expand the spring 46 and depress the rods 40 and 34, the latter being guided between the angles 33 so as to operate the toggle links 35 and depress the duplex damper members 37 and 38 to the dotted line position shown in Figure 2, thus completely cutting off the heating chamber and the radiator therein and permitting all the fresh, cold air entering the blower chamber 16 to pass from the latter through the motor board openings 15 into the by-pass chamber and directly out through the discharge opening 30 into the room where the apparatus is located. Reverse operation of the duplex damper is brought about by the thermostatic controlling means when the temperature in the room reaches a predetermined degree, whereupon the bellows or pump in the casing 44 is exhausted or reversed in operation, permitting the plunger 45 to rise under the lifting action of the lever 42, produced by the spring 46, this operation lifting the rods 40 and 34, which latter draws upon the toggle links 35, which in turn lift the members 37 and 38 of the duplex damper into the full line position of Figure 2. This opens the heating chamber 5, and simultaneously closes the by-pass chamber 29, exposes the radiator 6, and permits the air driven by the fans from the chamber 16 through

the openings 15 to pass downwardly into the heating chamber at the left of the full line damper position, Figure 2, and downwardly through the radiator into contact 5 with the surface of the water in the humidifying chamber 12, and upwardly through the radiator and outwardly to the right of the duplex damper, and through the discharge opening 30 into the room. Under 10 thermostatic control, the motor will also operate to regulate the position of the damper members 37 and 38 at any one of a plurality of positions between the full line positions shown in Figure 2 and the dotted line positions 15 in said figure, this regulation resulting in causing a portion of the cold air driven downwardly from the chamber 16 to pass down through the radiator and upwardly therefrom and out through the discharge 20 opening 30, and a portion of said air to pass directly through the by-pass chamber 29 and outwardly through the discharge opening 30. This operation provides for mixing hot and cold air to practically any degree required or desired, according to the regulation 25 of the thermostatic controlling means, since, according to the position of the damper members 37 and 38, more or less of cold air will pass from the chamber 16 into and out of 30 the by-pass chamber 29, and into and out of the heating chamber 5; and as the heated air in the chamber 5 rises through the radiator 6 for discharge through the by-pass chamber 29 and the opening 30, it will combine 35 and mix with the cold air passing from the chamber 16 through the chamber 29 above the damper members 37 and 38, and out through the discharge opening 30. Thus the temperature in the room is regulated by the admission 40 of more or less of cold and hot air, since the apparatus can deliver varying volumes of cold and hot air together, or hot air entirely, or cold air entirely. These are important functional results and especially 45 since, when it is desired to cool the room quickly, cold air can be driven directly thereto without being in any measure or degree tempered by hot air from chamber 5 or from the radiator 6. Thus, cooling of the room 50 where the unit is located can be accomplished quickly under automatic control and radical changes in temperature can be quickly brought about. It is also an important feature of my invention that the duplex damper 55 can be quickly, easily and positively manipulated, due to both the character of the actuating means, including a toggle joint, the form of the damper, the location of the latter in a by-pass chamber distinct from the 60 blower and heating chamber, and the disposition of said damper in the by-pass chamber. Another important feature of my invention is that, with the toggle mechanism shown, exact and accurate adjustments between extremes of the damper movements 65

can be obtained and held indefinitely under the control of the automatic thermostatic means located in the same room with the unit.

Recirculation through the apparatus of 70 Figures 1 and 2 can be brought about by manipulating the multiplex dampers at the inlet 49 and the chamber 22. That is to say, the bottom of the chamber 22 is provided with a multiplex damper 50, the members of 75 which are of the balanced type pivotally mounted centrally and connected by links 51 to a bar or rod 52, in turn pivotally connected to the upper end of a bell-crank lever 53 pivotally connected at the other end to a 80 rod 54, to which the links 55 are pivotally connected, said links being in turn pivoted, respectively, to the centrally pivoted balanced members 56 of a multiplex damper mounted in the casing member 57 of the inlet 85 opening to the motor and blower chamber 16. This structure is shown in detail in Figure 3, parts being omitted from Figure 2 in order to avoid confusion of lines. Thus when the multiplex damper 56 is open, as 90 shown in Figure 2, the multiplex damper 50 will be closed, while, when the latter is open, the inlet damper 56 will be closed, these operations being brought about by a rod connection 58 extended from the pivot of the bell-crank lever 53, a handle 59 outside the casing near the top of the blower chamber being provided for the purpose of easy manipulation. With the damper 50 open and the damper 56 closed, and the blowers in 100 operation, the air in the room may be drawn downwardly through the chamber 22 and driven from the motor chamber 16 downwardly into the by-pass and heating chambers, the damper members 37 and 38 being 105 manipulated automatically through the thermostatic control and motor mechanism, as previously described. This may be desirable in exceedingly cold weather or under circumstances requiring a rapid rise of temperature in the room where the apparatus is 110 located.

It is to be particularly noted that the structure of mechanism, in the form of my apparatus shown in Figures 1 and 2, provides for a compact arrangement of the motor 44 and its mechanism and of the blowers and their motor, and of the several multiplex dampers and manipulating mechanism in the upper chamber 16 of the apparatus. 115 This makes for economy of space and for elimination of obstructions and all functional devices, partitions, etc., in the heating chamber of the apparatus. The result is that the heating chamber is very greatly enlarged and the heating capacity of the apparatus is very greatly increased, and the very desirable result of thoroughly heating the air before it leaves the apparatus is brought about, since the cold air entering the blower 120 125 130

chamber may be driven down into the heating chamber, using the dampers in the by-pass chamber, in the solid line position of Figure 2, as a deflecting medium for directing the cold air, thus driven down from the motor chamber 16, to the back of the heating chamber and the radiating pipes or coils therein, from which back the air is deflected downwardly into the humidifying chamber 10 and in contact with the surface of the water in the pan or basin thereof, and from which, both under pressure and its natural tendency to rise, the hot air will return through the radiator at the front of the casing and pass 15 upwardly through the by-pass chamber and the discharge 30, the duplex damper again operating, in its full line position, Figure 2, as a deflector to direct the heated air through the discharge opening 30 and prevent it from 20 coming in contact with the cold air entering on the other side of the duplex damper. Thus the cold air entering at the left of the duplex damper is caused to descend and circulate downwardly through the radiator, and 25 then upwardly through the radiator, which latter acts upon the air for a comparatively long period resulting in quickly and materially raising the temperature of the air in the unit before discharge into the room 30 through the opening 30. This is also true in cases of recirculation of the air of the room through the apparatus bringing about a very rapid rise of temperature.

The effectiveness of the operation of the apparatus is greatly increased by the air chamber 4 provided in the front and sides of the base of the casing, since the provision of such air chamber prevents the outer casing from becoming overheated and radiating 40 its heat into the room after the duplex damper has been so manipulated as to supply cold air or only warm air to the room in which the apparatus is located. The insulating, or air chamber 4, or, in other words, 45 the double casing, also prevents the escape of heat from the apparatus except in predetermined manner; that is to say, the air is confined in the base of the apparatus and becomes intensely hot, enabling quick rises in 50 temperature to take place in the room where the apparatus is located. These are features of great importance since they bring about the desired effectiveness of temperature control through the medium of the duplex 55 damper automatically operated by the temperature in the room where the apparatus is located.

In the form of my invention shown in Figure 3, all the parts of the apparatus and 60 the various dampers which are similar to those shown in Figures 1 and 2 are indicated by the same reference characters. This will serve to identify the details of construction of the one apparatus with those of the other, 65 and accentuate the differences upon which

stress is to be laid in the following. Primarily, it is to be noted that the radiator 60 is different in form, though, in details of construction, is or may be the same as that shown in Figures 1 and 2. The difference in form 70 resides in the fact that the entire top of the radiator is flat or horizontal, instead of obtuse angular, as shown in Figure 2. The by-pass chamber is the same as in Figure 2, and the duplex damper 37—38 shown in full lines in 75 Figure 3 is the same, and is operated by the same mechanism, as in Figure 2.

In the apparatus shown in Figure 3, the air inlet 61 is arranged below the motor and blower chamber and directly below the motor 80 board support 62, which, in addition to having the front openings 15, as shown in Figure 2, is provided with the rear inlet opening 63 therethrough into the motor chamber at the back of the fan shields. The inlet is thus 85 made considerably below the window-sill or window opening shown in Figure 2, through the wall of the building and may be, consequently, directly through an opening in the wall or connected with a flue or air conduit 90 from some lower portion of the building according to convenience or architectural structure, or from some upper portion of the building exposed to the outside atmosphere from which cold, clean air can be taken into the 95 apparatus. The inlet opening 61 is barred and shut off from the by-pass and heating chambers of the apparatus by the back plate or baffle 64, which may be of any form or shape desired, and which extends from a 100 point adjacent the top of the heating chamber at the back thereof to connection with the motor board 62. In this form of my apparatus, the rod 65 connecting with the multiplex damper 56 at the inlet opening 61 is 105 considerably longer than the one 54 in Figure 2 and extends through the passage 63 in the motor board and into the inlet chamber 66.

In all other respects the Figure 3 form of 110 my invention is or may be substantially the same as shown in Figure 2, and the same mode of operation is carried out with the same functional results as detailed in connection with Figures 1 and 2. The importance of the 115 form of my invention shown in Figure 3 is that the apparatus may be made considerably smaller and lower, and can be adapted to other openings in the wall or walls of the building than the window openings, and the latter, in consequence, are left free, open and unobstructed. This is sometimes an important desideratum.

Recirculation is brought about in the form of my invention of Figure 3, the same as in 125 that of Figure 2; and the form of my invention in Figure 3 is subject to automatic, thermostatic and motor control, the same as described with reference to the form of Figure 2.

In Figure 4, I have shown a form of my invention wherein the inlet 67 is or may be in substantially the same position as in Figure 3; but, the motor or pump 68 is connected 5 to the bottom of the motor board and depends within the inlet chamber. The duplex damper is the same, and is operated by a rod guided in the same manner as in Figures 2 and 3, and the reference characters applicable 10 are applied to the similar structural features in Figure 4. The importance of this form of my invention resides in the fact that the lever 69 actuated by the plunger 70 of the motor and pivoted to said plunger and to the frame 15 of the latter is connected by an arm 71 having a pin and slot connection 72 with the lever 69 at its lower end, said arm 71 being carried by the rod 34, guided in the track between the angles 33. The lever 69 is extended 20 through a slot in the baffle 73 at the back of the inlet chamber 67, and also through a slot in the duplex damper member 37. This form of my invention makes for reduction in the size of the top of the casing or of the motor 25 and blower chamber, and thus reduction in the height of the apparatus. It also makes for simplicity and economy in construction of the means for manipulating the duplex damper under thermostatic control. In this 30 form of my invention the functional mode of operation of the multiplex damper, under thermostatic control and for all its uses and purposes, is the same as in the form of my invention disclosed in Figures 2 and 3.

35 In the form of my invention shown in Figure 5, I have provided for manipulating the duplex damper by hand operated means. This mode of operation is carried into effect by extending a slotted arm 74 laterally from 40 the rod 34, forming part of the toggle operating means for the duplex damper, which arm is part of a bell-crank lever, the other slotted arm 75 of which is connected at its lower end to a shiftable rod 76, which may be 45 slid or rotated in the sleeve 77 affording a bearing therefor by manipulating the handle 78. The bell-crank lever 74-75 is mounted upon a rod 79 fixed at its opposite ends in the side walls of the casing of the base near the 50 discharge opening 30. By moving the lower end of the arm 75 inwardly through the medium of the rod 76, the arm 74 of the bell-crank lever is lifted, thereby lifting the rod 34, carrying the toggle links 35, and thus 55 simultaneously lifting the members 37-38 of the duplex damper, the latter being thus shifted into the full line position shown in Figure 2. To shift the members of the duplex damper into the full line position shown 60 in Figure 5, the rod 76 is reversed in action, thus shifting the lower end of the arm 75 outwardly and lowering the arm 74, thus spreading the toggle and lowering the members of the duplex damper. Arm 74 is slotted 65 at its inner end so that the rod 34 may play

therein and arm 75 is slotted at its lower end so that a pin on rod 76 may play therein, thus giving the bell-crank freedom of movement for the purposes stated.

In other respects the form of my invention 70 in Figure 5 is the same as that shown in Figure 2, and the duplex damper of Figure 5 can obviously be automatically operated by the thermostatic controlling means shown in Figures 1, 2 and 3. On the other hand, the duplex 75 dampers shown in the other forms of my invention can be operated or controlled by hand, as shown, for example, in Figure 5. Other apparatus for manipulating the duplex damper may be employed; that is to say, the 80 duplex dampers may be manipulated by electrical means, pneumatic means, or by hand operated means as shown, for example, in Figure 5, or by thermostatically controlled means, as shown, for example, in the other 85 forms of my invention.

In Figures 2 to 5, inclusive, I have shown a deflector 80, connected to the sides of the base adjacent the pivotal point of the duplex damper 37-38, and depending into the heating chamber 5 at an angle such as to enable it to operate as a shunt or deflector for the air going into the radiator, or heating chamber and out of the latter through the discharge 90 30. This deflector may be more extensive 95 than shown in the drawings so as to enter considerably between the tubes of the radiator. Its function is to deflect the cold air entering the heating chamber through the bypass chamber when the duplex damper is in 100 the full line position shown in Figure 2. In this position of the dampers, the inner member 37 also operates as a deflector for the cold air driven down by the blower through the bypass chamber into the heating chamber. 105 The air thus deflected by the damper member 37 and the deflector 80 depending into the heating chamber is driven between the tubes of the radiator to the back wall of the heating chamber. From the back wall of the 110 heating chamber the air is deflected downwardly into the humidifying chamber where it is cleansed and humidified by the water in the pan 11. The clean air is then deflected from the surface of the water upwardly at 115 an angle to the front wall of the heating chamber, passing between the tubes of the radiator. From the front wall of the heating chamber the cleansed and heated air is deflected upwardly and also passes upwardly 120 through the heating chamber and between the tubes of the radiator into contact with the deflector 80 and the member 38 of the duplex damper. Thus the air is prevented from passing to the left of the deflector 80 into contact 125 or mixture with the cold air entering the heating chamber, and passes out thoroughly heated through the bypass chamber 29 and the discharge 30 into the room where the apparatus is located. This operation of my ap- 130

- paratus is important, since the air is twice heated in passing through the same radiator and the same heating chamber, at one time being driven downwardly and at the other time being driven upwardly and naturally also passing upwardly through the radiator. Of course, when the duplex damper is in the dotted line position shown in Figure 2, and in the full line position of Figures 3, 4 and 5, no cold or fresh air can enter the heating chamber in any circumstance. On the contrary, the cold or fresh air is driven by the blower directly into contact with the upper surface of the member 37 of the duplex damper, and from thence is driven directly through the by-pass chamber 29 and the discharge 30 into the room. Thus no heating of the cold air takes place and a quick drop of temperature in the room where the apparatus is located can be brought about. With the duplex damper set, either by hand or under thermostatic control at any intermediate position between the two extremes of full and dotted line positions shown in Figure 2, any desired mixture of cold and hot air can be brought about, since, according to the position of the members of the duplex damper, more or less of cold air will pass into the heating chamber and therefrom through the by-pass chamber and from the discharge 30, while more or less of cold air will pass through the by-pass chamber above the members of the duplex damper and mix with the hot air rising from the heating chamber and passing through the by-pass chamber 29 and the discharge 30. These modes of operation are highly important and upon them I desire to lay stress, since no other apparatus known to me can accomplish these functions.
- Another important feature of my invention is that the members of the duplex damper, under control of the several mechanisms shown, move the same distance in opposite directions; that is to say, member 37 moves the same distance from the full line, Figure 2, to the dotted line position that the member 38 does from the full line position to the dotted line position. Thus both members reach their respective seats 31 and 32 at the same time and reach the full line position from the dotted line position at the same time, moving at the same speed. It is also important that, when the members of the duplex damper are shifted to the dotted line position of Figure 2 and full line position of Figures 3, 4 and 5, the hot air chamber and the radiator are completely cut off, for the functional reasons heretofore stated.
- As shown in Figure 2, the apparatus is set in front of a window with its inlet casing member 57 at rest upon the window-sill at the bottom and having the window-sash lowered to contact with the casing at the top. Thus the window opening is utilized to the

extent desired, and no alteration is necessary in the building at the point where the apparatus is installed. This is also true of the form of apparatus shown in Figure 5.

In the form of apparatus shown in Figures 3 and 4, the inlet casing is fitted to an opening which goes directly through the wall of the building at any point below the window-sill or window opening, or at any point in the wall of the building remote from a window opening. Moreover, the inlet 61 may have communication with flues or a conduit extending from the outside of the building at some remote point, as heretofore suggested.

The location of the pumps which are operated by the thermostatic controlling means is such as to bring about a compact structure saving space in the casing and enabling the parts to be compactly arranged.

The inner lining or casing 3 may be composed of any material found suitable for the purpose; but, it is of my invention that heat insulating material may be used so as to prevent the radiation of heat from the inner casing wall 3 to the between chamber 4. However, it will be understood that the chamber 4 is an insulation medium capable of preventing the transmission of heat excessively to the outer casing members 1.

The position of the mouth of the shields surrounding the fans is important, since they are located at the front of the casing directly over the by-pass chamber, and in such relation to the latter and to the heating chamber below that, as the air slips off the blades of the fans due to centrifugal action of the latter, the tendency of the air is to pass directly through the by-pass chamber, when the duplex dampers are open, into the heating chamber and toward the rear wall of the latter. On the other hand, when the duplex dampers are closed so as to cover the heating chamber, the air driven by the fans will strike directly against the inner member of the duplex damper and be deflected or shunted outwardly directly through the discharge chamber 30.

In the unit of my present invention the following are important features:

The heating chamber is very large as compared with the by-pass chamber, thus enabling a large volume of air driven by the blowers to be quickly heated to a very high degree and discharged into the room from the apparatus, resulting in raising the temperature of the room to the predetermined degree very rapidly; the by-pass chamber is located at the top of the heating chamber and extends partly across the latter, this arrangement conserving space and enabling hot and cold air to be mixed in the apparatus just prior to its discharge into the room; the by-pass chamber is located between the heating and blower chambers in the direct path

of the air between the two; the blower chamber communicates directly with the by-pass chamber through the flared mouth of the fan shield, thus enabling the air driven by the 5 blower to be properly directed for discharge either directly from the by-pass chamber or through the latter into the heating chamber; the by-pass chamber leads directly from the blower chamber to the discharge outlet of 10 the unit, thus giving a short, direct path for the cold air from the outside of the building to the inside thereof through the apparatus; the delivery of air,—hot, cold or tempered,—from the unit is through the by-pass chamber; 15 the delivery of cold air to the heater or heating chamber is through the by-pass chamber; and, when the damper is closed over the heating chamber, no hot air can be dragged or induced from the heating chamber. 20

From the foregoing it will also be seen and understood that, when the duplex damper is closed to completely shut off the heating chamber, so that the cold air may 25 flow directly from the blower chamber through the by-pass chamber and be discharged into the room, the humidifying chamber and pan do not function; that is to say, the air entering the apparatus through 30 the inlet and driven by the blower directly into the room through the by-pass chamber, and completely by-passing the heating chamber, does not ordinarily need humidifying, since it carries more or less of moisture ordinarily sufficient for all purposes. However, 35 when the air entering the apparatus is driven through the heating chamber, its humidity is more or less eliminated and should be supplied with ordinary humidity which is furnished by the pan in the lower part of the apparatus before the hot air is discharged 40 into the room.

It will also be understood that the chamber 29, particularly termed "a by-pass chamber", 45 is also a mixing chamber or combined by-pass and mixing chamber; that is to say, viewing Figures 2 and 3 particularly, it will be seen that, under thermostatic control, the duplex damper may be shifted so that its members 50 37 and 38 may move gradually in opposite directions from the full line position shown in Figure 2 to the dotted line position shown in Figure 2, and vice versa. This gradual movement of the members of the duplex 55 damper may be for only a limited degree at any one time or during a short period of time, and, according to the control of the thermostatic means, the members of the duplex damper may be indefinitely held stationary 60 in any one of many intermediate positions between the extremes indicated by the full line position of the damper members in Figure 2 and the dotted line position of the damper members in said figure. In other words, 65 while the thermostatic controlling means

may, due to conditions in the room where the unit is located, slowly shift the members of the duplex damper from one extreme position to another, it may also shift the members of the duplex damper to any one of many intermediate positions and hold said members indefinitely in such positions. This capability of operation will be understood clearly upon reference to Figures 2 and 3, wherein I have indicated by dotted radial lines many 70 different intermediate positions of adjustment of the members of the duplex damper, or positions between extremes of movement of the members of said damper, said radial lines being lettered consecutively *a*, *b*, *c*, for example. In fact, during the operation of the apparatus, the thermostatic controlling means, as the temperature in the room rises, or reaches a predetermined degree of temperature, may shift the members of the duplex 75 damper continuously for a short period and through a short arc, or it may shift the members of the duplex damper slowly, degree by degree, and in each position hold the adjustment indefinitely. It will be understood 80 that such adjustments will depend entirely upon the temperature of the room of location of the unit. This ability of the thermostatic controlling means through the operation of the motor to make a predetermined adjustment, or to bring about an adjustment of the members of the duplex damper according to the temperature in the room of location of the unit, is a feature of great value commercially and practically, and is an important 85 feature of my invention. During the operation of the damper members as outlined in the foregoing, and while the said members are in any of the intermediate positions, cold air 90 driven down by the blowers through the passages 15 will go partly into the heating chamber and partly into the by-pass chamber; and that portion of the air which goes into the by-pass chamber will mix therein on its way 95 through the discharge 30 with the heated air emanating from and rising vertically through the radiator and heating chamber and passing into the by-pass chamber before discharge at 30. Thus, the hot air flowing from the heating chamber is mixed with cold air flowing 100 through the by-pass chamber, the mixture taking place in the latter, resulting in tempered air being discharged at 30 into the room of location of the unit.

As heretofore stated, the radiator is light 105 and has very high thermal efficiency, due to the fact that it is composed of thin tubes disposed horizontally in the heating chamber, the thin tubes terminating at opposite ends in headers or end chambers 7 and 8, which extend, in each instance, from front to rear of the machine or casing and from bottom to top of the heating chamber. The width of the headers may be of any predetermined extent, 115 dependent upon requirements of strength, 120

solidity and weight, or lightness. The headers, in addition to being chambers or tanks or closures for the opposite ends of the tubular radiating members, are also solid and extensive auxiliary radiators, having the ability as the result of primarily receiving and finally discharging the heated vapor or fluid used for heating purposes, to radiate a considerable amount of heat in addition to that which is radiated by the tubes 6. This structure is a material aid in giving a high degree of efficiency to the radiator and in rendering the unit capable of quickly heating the cold air drawn into and driven through the apparatus by the blower. In fact, in zero weather the apparatus is capable of raising the temperature of the air passing through the same and discharging it into the room of location of the unit at upwards of 80° F. On the other hand, under the thermostatic control the apparatus is capable of being operated on a 2° variation of temperature in the room of location, and of maintaining a room temperature of approximately any predetermined degree of temperature.

Having thus described my invention, what I claim and desire to secure by Letters Patent is:

1. A heating and ventilating unit consisting of a casing having means dividing it into a blower chamber, a heating chamber, a humidifying chamber, and a by-pass chamber, the by-pass chamber being located entirely above the heating chamber and at the front of the casing; a damper located to operate between the heating chamber and the by-pass chamber and being sufficiently extensive to entirely close the heating chamber and define the bottom of the by-pass chamber; and means for actuating the damper so as to control the temperature of the air delivered by the unit.

2. A heating and ventilating unit comprising a casing having means dividing it into a blower chamber, a by-pass chamber, and a heating chamber, the said several chambers being located the one under the other in the order named, and the by-pass chamber having a damper operating therein to entirely cut off the heating chamber from the blower chamber and define the bottom of the by-pass chamber for the purpose of controlling the passage of cold air from the blower chamber through the unit and the discharge of air into the room in which the unit is located.

3. A heating and ventilating unit comprising a casing having a heating chamber and a by-pass chamber, the one located above the other; a duplex damper operating in the by-pass chamber and adapted to cut off the heating chamber entirely from the by-pass chamber and to define the bottom of the by-pass chamber; and means for actuating the damper to control the size of the passage between the two chambers.

4. A heating and ventilating unit comprising a casing having a by-pass and heating chamber; a damper located between the two chambers and, when in open position, being adapted to divide the by-pass chamber, said damper being of duplex form; and means for actuating the two parts of the damper to control the admission of cold air to the heating chamber and the discharge of hot air from the heating chamber.

5. A heating and ventilating unit comprising a casing divided into a blower chamber, a heating chamber, and a by-pass chamber, the latter being located between the other two chambers; a damper of duplex form mounted to operate in the by-pass chamber; and means for actuating the two parts of the damper to control the admission of cold air to the heating chamber and the discharge of hot air from the heating chamber.

6. A heating and ventilating unit comprising a casing divided into a blower chamber, and by-pass and heating chambers located below the blower chamber; a damper of duplex form mounted to operate below the blower chamber and to define the bottom of the by-pass chamber; and means for actuating the two parts of the damper to control the admission of air to and the delivery of air from the by-pass and heating chambers.

7. A heating and ventilating unit comprising a casing having means dividing it into a blower chamber, a by-pass chamber, and a heating chamber; and a duplex damper located between the heating and by-pass chambers so as to control the inlet to and the outlet from the heating chamber and to define the bottom of the by-pass chamber; and means for actuating the duplex damper to bring about the foregoing control and so that the heating chamber may be completely cut off from the blower chamber.

8. In a heating and ventilating unit having means dividing its space into a heating chamber and a by-pass chamber located wholly above the heating chamber; a duplex damper located in the by-pass chamber and adapted to cut the same off from the heating chamber; and toggle means for actuating the parts of the damper.

9. In a heating and ventilating unit having means dividing its space into a heating chamber and a by-pass chamber located wholly above the heating chamber; a duplex damper located in the by-pass chamber and adapted to cut the same off from the heating chamber; toggle means for actuating the parts of the damper; and means for automatically controlling the operation of the toggle means.

10. A heating and ventilating unit comprising a casing having a blower chamber, a heating chamber and a by-pass chamber; a duplex damper located and operating in the by-pass chamber; toggle means for actuating the parts of the damper; a motor in the

- blower chamber; and connections between the motor and toggle for actuating the latter.
11. A heating and ventilating unit comprising a casing having a by-pass and heating chamber; a damper located between the two chambers and, when in open position, being adapted to divide the by-pass chamber; means for actuating the damper to open and close the passage between the two chambers; and a deflector depending into the heating chamber and adapted to shunt the air passing between the chambers in two different directions.
12. A heating and ventilating unit having two intercommunicating chambers, a two-part damper, and means whereby the parts of the damper may be operated in opposite directions, whereby to entirely close one of the chambers and open the other.
13. A heating and ventilating unit comprising a casing divided into a plurality of chambers, one of the chambers being at the top of the casing and adapted to contain blowers and a motor for operating the latter; another of the chambers being at the bottom of the casing and adapted to contain a heating element; another and smaller chamber being located between the heating and blower chambers and having a damper operating therein adapted to shut off the heating chamber from the blower chamber; and still another chamber located between the heating and blower chambers and in rear of the smaller chamber and communicating with the blower chamber to admit fresh air thereto.
14. A heating and ventilating unit comprising a casing divided into a plurality of chambers, one of the chambers being at the top of the casing and extending from front to rear thereof and adapted to contain blowers; and a motor for operating the latter; another of the chambers being at the bottom of the casing and extending from front to rear thereof and adapted to contain a heating element; another and smaller chamber being located between the heating
- and blower chambers and at the front of the casing and having a two-part damper operating therein adapted to entirely shut off the heating chamber from the blower chamber by defining the bottom of the smaller chamber; and still another chamber located between the heating and blower chambers and at the rear of the casing and arranged to communicate with the blower chamber to admit fresh air thereto.
15. A heating and ventilating unit comprising a casing having a discharge opening at its front and divided into a plurality of chambers, one of the chambers being at the top of the casing and adapted to contain blowers; and a motor for operating the latter; another of the chambers being at the bottom of the casing and adapted to contain a heating element; and two other chambers located between the heating and blower chambers, one being adapted for the inlet of fresh air and being in communication with the blower chamber, and the other being adapted to by-pass the fresh air driven from the blower chamber and being in communication with the latter and with said discharge opening; and means between the heating chamber and the by-pass chamber for isolating the heating chamber from the blower chamber.
16. A heating and ventilating unit comprising a casing divided into a blower chamber, a by-pass chamber and a heating chamber, the several chambers being located one above the other; and a damper of duplex form mounted between the heating and by-pass chambers; and means for actuating the two parts of the damper simultaneously in opposite directions and at approximately the same speed, whereby the said two parts of the damper may control the admission of cold air into the heating chamber and the discharge of hot air from the heating chamber.

MICHAEL J. CALLAHAN.
